UNITED STATES PATENT OFFICE.

WILLIAM HECKERT, OF YONKERS, NEW YORK, ASSIGNOR TO BENJ. BUTTERWORTH, TRUSTEE, OF CINCINNATI, OHIO.

CHAIN GRIP FOR CABLE ROADS.

SPECIFICATION forming part of Letters Patent No. 431,658, dated July 8, 1890.

Application filed February 13, 1888. Serial No. 263,870. (No model.)

To all whom it may concern:

Be it known that I, WILLIAM HECKERT, a citizen of the United States, residing at Yonkers, in the county of Westchester and State of New York, have invented certain new and useful Improvements in Chain Grips for Cable Roads; and I do hereby declare the following to be a full, clear, and exact description of the invention, such as will enable others skilled in the art to which it appertains to make and use the same.

My invention consists of the herein described and illustrated improvements in chain grips for traction-cable railroads.

15 In the drawings, Figure 1 represents the car-body with the gripping apparatus and cable-conduit in longitudinal section, together with a side view of the cable in the conduit. Fig. 2 represents a plan view of the running-gear and chain grip, together with the customary form of brake and the apparatus for operating the grip and the brake. Fig. 3 represents a section of a portion of the friction apparatus for the grip, showing the rectangular frame in combination with the axle-box, the frame being in its lowest position of vertical adjustment. Fig. 4 represents the same, the frame being in its position of medium vertical adjustment. Fig. 5 represents a side 20 view of the adjustable frame and its axle-box, together with the pinion and rack for effecting its adjustment.

Throughout the drawings like letters refer to like parts.

35 In Fig. 1, M represents the car-body, supported in the usual manner by wheels W W' and axles X X'. (Best shown in Fig. 2.)

C is the cable running in the conduit C' and having the trucks C''.

40 The chain grip consists of the sprocket-chain V, having the three sprocket-teeth A, A', and A'', which latter engage with the trucks C'' on the cable. When the friction apparatus, which consists of the rectangular frame J, having the semicircular end pieces K K', in which are set the friction-rollers k k', &c., together with the curved pivoted shields B B', surrounding the semicircular end pieces, is relaxed, the sprocket-chain V 45 runs freely upon the rectangular frame, and the car is independent of the cable. At-

tached to the pivoted shields B B' are the rods d d', which are in turn attached to the chains wound about the drums G G'. These drums are turned by the worm-gearing H H', which is controlled by the hand-wheels h h'. The other ends of the chains are attached to rods b b', which extend to the brake-beam Y, to which latter is connected the ordinary 55 brake apparatus.

When either hand-wheel h or h' is turned in one direction, the chain attached to the rod d or d' is wound up upon the drum and the swinging shield B or B' is swung out away from the rectangular frame J and the sprocket-chain V is subjected to friction. The chain, which has hitherto been supposed to run freely over the rectangular frame and the pulleys k k', &c., is now locked to said frame and the car is compelled to move along with the 60 cable. When the hand-wheel is turned in the opposite direction, the friction apparatus of the chain grip, whose construction and operation has been above described, is released, and a continued turning of the hand-wheel 65 brings the brake into operation in the well-known way.

It is evidently desirable when shifting the car from one track to another that the chain grip and its supporting-frame may be lifted, 70 so that the sprocket-teeth A A', &c., shall be freed from the slot in the cable-conduit C'. To accomplish this I have designed the following apparatus.

The rectangular frame J is formed into a 75 species of truss by the diagonal braces n n'. Upon the axles X X' are the boxes R R', in which the frame J slides vertically. Connecting the boxes R R' are the rods T T', which support midway of their length the 80 vertical guide O. In the boxes and the guide O are journaled two pinioned shafts r r', having at their ends the pinions z z and z' z'. These pinions gear into the racks U, one of 85 which is clearly shown in Fig. 5. The frame J is supported at the points m m' by the levers F F', which are in turn pivoted to the car-body at the points l l', and are provided with the treadles f f' and the stiff counter-balancing-springs S S'. 90

In the operation of my device the driver may stand at either end of the car and by

means of the hand-wheel control both the grip and the brake. By placing his foot on the treadle above described he lifts one end of the frame J, and this motion is transmitted by 5 means of the racks and pinions described to the other end of the frame J, so that the latter moves always parallel to itself, although the lifting-power is originally applied only at one end of the frame. The springs S S' are so 10 designed as to merely balance the weight of the frame J and its encircling chain, so that the only force which the operator needs to use is that sufficient to overcome the friction of the apparatus. It is thus evident that the 15 operation of my chain grip together with its withdrawal from the conduit-slot and the operations of the brake are completely under the control of the car-conductor at whichever end of the car he may be placed.

20 I am aware that in systems of this nature the friction apparatus and the brake have both been under control of the same chain and drum in previously-designed apparatus; but so far as I am aware in all mechanism of 25 this description the chain has been wound directly upon the shaft to which the hand-wheel is attached. This has necessitated a complicated arrangement of pawls, which interferes with the convenient and rapid operation of the grip and brake. By using the 30 worm-gearing, as above described, I have obtained a self-locking apparatus which dispenses with the pawls and greatly simplifies the mechanism and heightens its efficiency.

35 The swinging pivoted shields B B' are provided with ports which correspond with the friction-rollers k k', &c.

The advantage of this apparatus is that when the friction is applied to the chain by 40 the outward swinging of the shields there is sliding friction between the links of the chain and the shield; but when the friction apparatus is relaxed the friction-rollers peep through the ports in the shield and the links 45 of the chain roll easily upon them.

The part of the chain-links marked V, Figs. 1 and 2, is properly a projecting web in line with the several sprocket-teeth and forming a continuous guide which runs in the slot of 50 the conduit. Thus while the car stands still or is slowing down the part V serves to guide these sprocket-teeth into the slot as they pass around the rectangular frame J.

Having therefore described my invention, 55 what I claim as new, and desire to protect by Letters Patent, is—

1. In a chain-grip apparatus for traction-cable railroads, the combination of the rectangular frame, the surrounding sprocket-chain, the hinged shields pivoted at the ends 60 of the frame, and suitable apparatus for forcibly swinging the pivoted shields away from the frame, substantially as described.

2. In a chain-grip apparatus for traction- 65 cable railroads, the combination of the rectangular frame provided with semicircular end pieces and friction-rollers, the curved

and pivoted shields surrounding said semicircular end pieces and having ports corresponding to the friction-rollers, the encircling 70 sprocket-chain, and suitable apparatus for forcibly swinging the pivoted shields away from the frame, substantially as described.

3. In a chain grip for traction-cable railroads, the rectangular vertically-movable 75 frame adjustable relative to the car-body, in combination with the axle-boxes in which the frame slides, substantially as described.

4. In a chain grip for traction-cable railroads, the rectangular vertically-movable 80 frame, in combination with the axle-boxes, the pinion-shaft journaled in the axle-boxes, the pinions on the shaft, and the racks upon the frame, substantially as described.

5. In a chain grip for traction-cable railroads, the rectangular vertically-movable 85 frame, in combination with the axle-boxes, the pinion-shaft journaled in the boxes, the pinions on the shaft, and the racks upon the frame, together with suitable apparatus for 90 lifting the frame, substantially as described.

6. In a chain grip for traction-cable railroads, the rectangular vertically-movable 95 frame, in combination with the axle-boxes, the pinion-shaft journaled in the boxes, the pinions on the shaft, and the racks upon the frame, together with the pivoted levers, the treadles, and the counterbalancing-springs, substantially as described.

7. In a chain grip for traction-cable railroads, the combination of the sprocket-chain, the friction apparatus for the same, the drum, the brake-beam, the chain wrapped about the drum and attached at one end to the friction apparatus and at the other to the brake-beam, together with the hand-wheel and worm-gear for operating the drum, substantially as described.

8. In a chain grip for traction-cable roads, links provided with ribs or flanges in line 100 with the several sprocket-teeth and serving to guide the said sprockets into the slot of the cable-conduit, substantially as described.

9. In a traction-cable road, the mechanism connecting the car with the cable, consisting 115 of the combination of a vertically-movable frame and a series of horizontally-movable arms sustained by said frame, substantially as described.

10. In a chain grip for traction-cable roads, 120 the combination, with the car and the moving cable, of a mechanism for connecting the same, consisting of a vertically-movable frame, a series of movable arms sustained by said frame, and suitable lifting mechanism 125 extending from said frame to the platform of the car, substantially as described.

In testimony whereof I affix my signature in presence of two witnesses.
